Primary Examiner — S. Bryan Reinholdt, Jr.Assistant Examiner — Julia S Folkart(74) Attorney, Agent, or Firm — Craft Chu PLLC;
Andrew W. Chu(57) CLAIM

The ornamental design for a padset for a pedicure spa chair as shown and described.

DESCRIPTION

FIG. 1 is an upper side perspective view of the padset for a pedicure spa chair according to my design;

FIG. 2 is a side elevation view thereof;

FIG. 3 is an opposite side elevation view thereof;

FIG. 4 is a front elevation view thereof;

FIG. 5 is a rear elevation view thereof; and,

FIG. 6 is a top plan thereof.

A bottom plan view is not shown, and there is no claim to any design features solely viewable in the bottom plan view.

1 Claim, 6 Drawing Sheets(56)
